UNITED STATES PATENT OFFICE.

RICHARD J. KELLY, OF SYRACUSE, NEW YORK.

MACHINE FOR CLEANING CATCH BASINS.

Application filed April 26, 1922. Serial No. 556,790.

To all whom it may concern:

Be it known that I, RICHARD J. KELLY, a citizen of the United States, residing at Syracuse, in the county of Onondaga and 5 State of New York, have invented certain new and useful Improvements in Machines for Cleaning Catch Basins, of which the following is a specification.

This invention relates to a machine for 10 cleaning catch-basins, and has for its object to provide a portable device of the class which consists of a wheeled vehicle which may be driven or hauled from place to place and positioned over catch basins, sumps, 15 and the like, for removing water and semi-liquid sediment which are retained by the catch basin. A further object is to provide a novel swingable conveyor, which is foldably mounted on the truck of the vehicle, 20 and which may be readily and quickly elevated, for positioning its receiving end over the manhole of the catch-basin, and then lowered into the basin to different depths. A further object is to provide means for adjusting the conveyor after it is lowered into 25 the basin for lifting the contents of the basin from different parts thereof. A further object is to provide means for operating the conveyor for elevating the contents 30 of the basin. And a further object is to provide auxiliary means for conveying the elevated material from the primary conveyor to a dump wagon.

I attain these objects by the means set 35 forth in the detailed description which follows and as illustrated by the accompanying drawings, in which—

Figure 1 is a side elevation of the complete device, folded up ready for transportation or operation. Fig. 2 is a top plan view of the same. Fig. 3 is an enlarged detail view of the gearing employed for moving the conveyor from the horizontal to the vertical position. Fig. 4 is a similar view 45 of a portion of the gearing employed for raising and lowering the conveyor relatively to a catch basin. Fig. 5 is a similar view of other parts of the same gearing. Fig. 6 is an elevational view of the conveyor; 50 showing by full and dotted lines the vertical movements of the conveyor relatively to the catch basin and a dump wagon. Fig. 7 is a broken central vertical section taken on line 7—7 of Fig. 2. Fig. 8 is a detail 55 sectional view taken on line 8—8 of Fig. 7. Fig. 9 is a similar view taken on line 9—9 of Fig. 7. Fig. 10 is a top plan view of the frame that pivotally supports the conveyor.

In the drawing, the vehicular portion of the machine consists of a double truck, comprising a horizontal frame 2 preferably made of flat bar metal, whose spaced side rails 2' are arranged V-shaped, as shown by the full and dotted lines in Fig. 2, and the forward end or point of the V being formed into a bearing 2^a, which supports a pivot pin 3' carried by the swiveled front truck 3, the latter being mounted on wheels 4. 4' represents a tongue or handle for guiding the vehicle, which is connected in the usual manner to the truck 3. At the rear end of the frame the rails 2' are spread apart and provided with depending arms 2^b which are perforated to receive the axle of the rear truck 5, which includes wheels 5'. The rear end-portion of the frame is braced by similar angular rods *a*.

The cleaning of the catch basin *c* is effected by a belt conveyor 6, which may follow any suitable or usual construction, and in the present showing consists of an endless flexible member 6', and regularly spaced buckets 6^a supported by said member (see Figs. 1, 2 and 7). When the rear end of the conveyor is lowered into the catch-basin, the said buckets scoop up the water and mud and carry the same upwardly to a suitable height, from which the refuse is discharged into a dump-wagon or other receptacle *d*, by means of a spout 7, which is preferably hinged to the opposite or forward end of the conveyor support and is adjustable by means of a rod 7' and a guide 7^a, the latter being carried by the conveyor support. 8 represents the elongated hollow casing or support which encloses the conveyor 6, the said support preferably having an upturned front end portion 8', as best seen in Figs. 1 and 6. The conveyor 6 is partially mounted on rollers 9 disposed within the housing 8, preferably adjacent the angle 8', and at its rear end. The forward end of the conveyor (member 6') is preferably mounted upon and driven by spaced sprockets 9', which are rigid on a shaft 9^a, one end of the said shaft extending through the casing 8 and supporting a sprocket 10. For this purpose the member 6' is perforated along its lateral edges for receiving the teeth of the sprockets 9' (see 110

Fig. 2). The conveyor 6 is operated by means of a chain 10' which engages the sprocket 10, and a similar sprocket 10^a, the latter being supported at one side of the 5 casing 8 intermediate its ends. The sprocket 10^a is mounted on a shaft 10^b, whose outer end is square, and to which a crank 11 may be applied for operating the conveyor and related parts. The angular front-end portion 10 of the housing 8 is provided for shifting the center of gravity of the housing rearwardly of the normal vertical axis of the housing when the latter is positioned as shown in Fig. 6 for preventing the accidental return of the housing to the horizontal position shown in Figs. 1, 2, and 7.

The conveyor housing 8 is pivotally connected to, and is supported by, the forward end of a rack 12, which is disposed in the 20 line of the longitudinal axis of the frame 2 and the casing 8, by means of a T-shaped part 13, which is provided with a horizontal pin 13', and a vertical pin 13^a (see Figs. 1, 6, 7 and 8). By this construction and 25 arrangement the casing may be rotated or swung vertically on the pin 13', or it may be swung horizontally on the pin 13^a, in a well-known manner. The foregoing parts constitute practically the only positive support 30 for the conveyor 6 and its housing 8. When the conveyor is in the folded or horizontal position, shown in Figs. 1 and 2, the forward end portion of the casing 8 rests by gravity upon a standard 14, which rises 35 from the forward end of the frame 2. The rear end of the rack 12 is adjustably mounted in a block 15, which is rigidly disposed between the converging ends of a triangular swinging frame 16 and the latter is pivotally 40 mounted between the rails 2' of the truck frame, by means of bolts 16'. For this purpose the block 15 is provided with a longitudinal slotted opening 15', which slidably receives the said rack 12, and the 45 said rack is held in place and prevented from accidental release from the said block, by means of a spring 15^a, which is provided with a tooth 15^b that engages a notch 15^c in the top edge of the rack (see Figs. 5 and 7). 50 The conveyor 6 and its casing 8 are elevated from the positions shown in Figs. 1, 2 and 7, to that shown in Fig. 6, by means of a curved or quadrant-shaped rack 17, and a pinion 17' the latter being mounted on a 55 shaft 17^a, the said shaft being supported by a bracket 17^b carried by one of the rails 2', and also by a bracket 17^c, which is mounted on a cross-bar 17^d, that extends transversely between the rails 2'. One end of the shaft 60 17^a projects through the bracket 17^b and is square, to receive the crank 11, by means of which the pinion 17' is rotated, for raising and lowering the conveyor (see Figs. 1, 2, 3 and 6). After the conveyor is swung 65 upwardly to the vertical or operating posi-

tion, shown in Fig. 6, its rear or lower end may be lowered into the catch-basin c, by the operator shifting the crank 11 to the square end of the shaft 12', upon which is mounted a pinion 12^a that engages the teeth 70 of the rack 12 (see Figs. 5, 6 and 7), and then by turning the said shaft towards the right. This operation moves the conveyor and its casing downwardly into the catch-basin c, as from the full line to the dotted line position, shown in Fig. 6. 12^b represents a ratchet wheel which is rigid on the shaft 12', and 12^c represents a pawl which is pivoted to the block 15, and engages the ratchet, for locking and holding the conveyor and its housing in any desired position relatively to the catch-basin c, and the main frame 2. That is to say, when the crank 11 is applied to the shaft 12' for lowering the conveyor into the catch-basin, the operator releases the pawl 12^c while he turns the crank 11 towards the right, which lowers the conveyor, as from the full line to the dotted line position in Fig. 6. In case of any variation in the depth of the catch-basins, or if for any other reason it is desired to stop the downward movement of the conveyor before it reaches the bottom of the basin, the operator lets go of the pawl 12^c, and it instantly stops and holds the conveyor from any further downward movement until the pawl is released, or until the conveyor is moved in the upward direction by the opposite rotation of the shaft 12'. After the conveyor is thus lowered into the catch-basin, the operator shifts the crank 11 to the sprocket shaft 10^b, and by rotating said shaft towards the right, sets the conveyor 6 in motion in the proper direction, for elevating the contents of the basin c to the top of the housing 8, and discharges the same, by means of the spout 7 into the dump wagon d. In practice, preparatory to cleaning the catch-basin the rear truck 5 is positioned so that the wheels 5' straddle the basin as best seen in Fig. 6.

My improved catch-basin cleaner is extremely simple, and when constructed and operated, as herein shown and described, is capable of cleaning the basins in much shorter time and with less inconvenience and expense, than any other method or device heretofore employed for the purpose, so far as I am aware. The foldable nature of the device renders it compact, and by reason of the several peculiar and novel operating mechanisms, it requires but a few minutes to adjust the conveyor parts, for making them ready to perform the work. In the present showing the several movable parts of the machine are operated by hand, by means of the crank 11, but it is understood that any other power may be employed in a well known manner, although such connections are not shown.

Having thus described my invention what I claim, is—

1. A machine for cleaning catch-basins, including a horizontal frame, a swingable member pivoted to said frame, an endless conveyor supported in parallel relation to said frame, a housing for the conveyor universally pivoted to said member, means for swinging said housing and said member 5 rearwardly for positioning said parts vertically above a catch-basin, means for moving said housing towards and away from said catch-basin, and means for operating said conveyor irrespective of the position of 10 said housing.

2. A portable machine for cleaning catch-basins, comprising a vehicle having a horizontal frame, an endless belt conveyor normally supported in horizontal position by 20 said frame, a swinging member pivoted to said frame and having a reciprocatable part, means for pivotally connecting said conveyor to the reciprocatable part of said member, means for swinging said conveyor and said 25 member from the horizontal to the vertical position, a mechanism carried by said member for projecting one end of said conveyor into a catch-basin and for withdrawing said member from said basin, and means for operating said conveyor for elevating the contents of the catch-basin.

3. A catch-basin cleaner, comprising front and rear trucks connected by a frame, an endless belt conveyor normally positioned 35 horizontally on the said frame, a housing for said belt, a swinging member pivoted towards the rear end of said frame including a rack, means for pivotally connecting said housing with one end of said rack, a mechanism for moving said housing from the horizontal to the vertical position, means operatively engaging said rack for moving said housing vertically towards and away from a catch-basin, and a mechanism for operating 40 said conveyor for elevating the contents of the basin.

4. A catch-basin cleaner, comprising a wheel vehicle having a horizontal frame, a belt conveyor mounted horizontally above 50 said frame, a swinging support member for said conveyor pivoted near the rear end of the frame, means for pivotally connecting said conveyor with the forward end of said member, a mechanism for moving said conveyor and said member from the horizontal 55

to the vertical position, means carried by said member for moving said conveyor vertically relatively to said member and said frame, means for preventing the accidental swinging of said conveyor from the vertical towards the horizontal position, and means for operating said conveyor for removing the contents of a catch-basin.

5. A machine for cleaning catch-basins, comprising a vehicle having a front and rear truck connected by a frame, a swinging member pivoted near the rear end of said frame, a reciprocatable rack carried by said member and movable in the line of the longitudinal axis of the member, an endless belt 60 conveyor, a housing for said conveyor, means for pivotally connecting said housing to said rack, a mechanism for swinging the forward end of said member rearwardly for positioning said housing vertically, a mechanism for moving said housing vertically towards and from a catch-basin, means for locking and holding said housing in different positions relatively to the bottom of the basin, and means for rotating said conveyor for removing the contents of the basin.

6. A machine for cleaning catch-basins, comprising a frame, a support adjustably mounted on the frame, an endless conveyor, and means mounting the latter on the support for universal movement.

7. A machine for cleaning catch-basins, comprising a frame, an endless conveyor, a support pivoted at one end to the frame, and means universally mounting the conveyor on 80 the opposite end portion of the support.

8. A machine for cleaning catch-basins, comprising a frame, an endless conveyor, a support pivoted to the frame and having an extensible part, and means universally 85 mounting the conveyor on the extensible part.

9. A catch-basin cleaner, comprising a wheeled frame, an endless belt conveyor, a vertically swinging member pivoted on said frame, a rack extension for the member, a pinion journaled on the member for sliding the rack, means for pivotally mounting the conveyor on said rack, a mechanism for swinging the member vertically and comprising a part carried by the frame and a part engaging the swinging member.

In testimony whereof I affix my signature.

RICHARD J. KELLY.
